(57)

CLAIM

The ornamental design for the saxophone guards, as shown and described.

DESCRIPTION

FIG. 1 is a perspective view of the saxophone guards;

FIG. 2 is a right side view of the saxophone guards;

FIG. 3 is a left side view of the saxophone guards;

FIG. 4 is a front view of the saxophone guards;

FIG. 5 is a rear view of the saxophone guards;

FIG. 6 is a top plan view of the saxophone guards; and,

FIG. 7 is a bottom plan view of the saxophone guards.

The portions of the saxophone in broken lines are shown for illustrative purposes only and form no part of the claimed design.

1 Claim, 5 Drawing Sheets
